UNITED STATES PATENT OFFICE.

GEORGE G. SCHUELE AND ELMER E. ILGENFRITZ, OF CLEVELAND, OHIO.

VACUUM-CLEANER.

1,053,653.

Specification of Letters Patent. Patented Feb. 18, 1913.

Application filed March 2, 1912. Serial No. 681,036.

To all whom it may concern:

Be it known that we, GEORGE G. SCHUELE and ELMER E. ILGENFRITZ, citizens of the United States, residing at Cleveland, in the 5 county of Cuyahoga and State of Ohio, have invented certain new and useful Improvements in Vacuum-Cleaners, of which the following is a specification.

The present invention relates to improvements in vacuum cleaners, and is designed especially as a carpet cleaning device.

The object of the invention is to improve the construction and operation of the suction type of carpet cleaners in several particulars. The hand operated machine of this type embodies mechanism which may be continuously operating, although the machine and its driving means are actuated and operatively driven only upon the forward 20 stroke or movement of the cleaner, the movement being similar to the ordinary carpet sweeper.

The embodiment of the invention according to our improvements provides a simple, 25 compact, and durable instrumentality for the purpose designed, and the initial or first cost of the device is comparatively low.

The invention consists essentially in the novel features of construction and combination 30 and arrangements of the nozzles, suction chambers, the fan casings, etc., as will be more particularly pointed out in the following specification and claims.

In the accompanying drawings we have 35 illustrated one example of the physical embodiment of our invention constructed according to the best mode we have so far devised for the practical application of the principles.

40 Figure 1 is a top plan view of a carpet cleaner embodying the principles of our invention. Fig. 2 is a vertical sectional view on a plane indicated by line 2—2 Fig. 1.

Fig. 3 is a vertical sectional view on a plane 45 indicated by line 3—3 of Fig. 1. Fig. 4 is a vertical sectional view on a plane indicated by line 4—4 of Fig. 1. Fig. 5 is a vertical sectional view of the device on the plane of shafts 11 and 14.

50 The cleaning device as illustrated in the drawings is specially intended for household or similar use, and is to be manipulated in the manner similar to the ordinary type of carpet sweeper employing brushes, 55 and drawn back and forth over the carpeted

floor by hand. For this purpose the usual handle 1 is provided, but for convenience in illustration the handle has been broken off, and the device may be propelled back and forth upon the wheels 2, 2, which are loosely journaled upon the shaft 3.

The shaft 3 is supported in bearings 4, 4, and is to be rotated through the medium of the traction or driving wheels (in forward direction only) through the medium of a 65 disk 5, which is keyed to the shaft, and a series of pivoted pawls 6 on the disk. These pawls are adapted to engage ratchet teeth 7 fashioned on the wheels, so that, when the wheels are rotating in the direction of the 70 arrow in Fig. 4 the teeth engage the pawls to rotate the disk and thus turn the shaft. In this manner the shaft is rotated only upon the forward movement of the wheels, 75 the pawls being released from the teeth when the wheels are turned backward, and to prevent dislocation of the pawls, lugs 8 are provided, as will be understood.

As is clearly illustrated in Fig. 1 the invention as embodied in its physical form includes a pair of fans, as 9, 9, inclosed within casings 10, 10, and supported to rotate upon a common shaft 11. The fans are driven from the driving shaft 3 through the medium of the driving gear wheel 12, which 85 meshes with a pinion 13 on shaft 14 supported between the fan casings. In addition to the small pinion 13, the shaft carries a larger gear 15, which engages a pinion 16, rigid with a cup 17 and loose on the fan 90 shaft 11. The cup 17 is formed with an interior series of notches or teeth 18 with which are adapted to engage a series of pivoted pawls 19 on the disk 20, the latter being rigid with the fan shaft 11. Through 95 this described train of gears and driving pawls the fan shaft is driven to rotate the fans in one, the forward direction, only.

The two fan casings are connected and braced by means of the webbed plate 21, 100 which is bolted, as by means 22 to the casings and holds them rigidly in position.

Integral with each fan casing and projecting forwardly and downwardly therefrom is a nozzle portion 23 formed with an 105 open outer end 24, a flat passageway 25 which increases in height and merges into the intake chamber 26 that opens into the fan casing. Each fan casing is provided with an outlet pipe 27, to which the open 110

mouth 28 of a bag 29 is attached, and the bag is attached to the handle 1 by means indicated at 28'.

In addition to the web plate 21, the duplex parts of the device are connected and secured together by means of the ears or flanges 30 which are perforated for the reception of the bolt 31.

In operating the device, the machine is 10 propelled forwardly on its wheels 2, by pushing on the handles, and if desired may be alternately pushed forward and drawn backwardly, but in either operating the machine by continuous forward movement, or 15 an alternate forward and rearward movement, it will be understood that the fan mechanism is driven only in one direction and that the forward direction of travel of the wheels 2. By use of the double ratchet 20 or clutch arrangement, one in the driving wheels and the other on the fan shaft, the wheels are driven in one direction only to actuate the fan actuating mechanism, and when the device is drawn back or reversed in 25 its movement, the gears in the driving train stand still, and the fan is permitted to rotate without unnecessary retarding friction or power in driving the mechanism. The driving clutch mechanism in each of the 30 wheels rotates the shaft 8 which in turn revolves the driving gear 12, and through the medium of this gear the clutch mechanism within the disk cup 17 drives the fan shaft to rotate the fans. The continued manipulation 35 and propelling of the machine causes the fans to attain high speed and a vacuum is quickly created in the casings. The suction then draws dirt, dust, etc., through the mouth 24, up through the passageways 25, 40 the intakes 26, thence through the outlet pipes 27 into the twin mouths of the bag 29.

After the bag 29 has been sufficiently filled, it may be detached, and replaced by an empty one, and the operation of cleaning resumed.

From the above description taken in connection with our drawings it is evident that we have provided a device for this purpose which fulfills the conditions set forth as the objects of our invention.

Having thus fully described our invention what we claim as new and desire to secure by Letters Patent is:—

1. The combination with supporting traction wheels, duplicate fan casings and a fan in each casing, of a nozzle portion integral with each casing and opening thereinto and provided with an open mouth, a driving shaft and driving gear wheel actuated by said traction wheels, a fan shaft and a clutch 55 and gear thereon, and an intermediate shaft with gears thereon for transmitting rotation from the driving shaft to the fan shaft.

2. The combination with a driving shaft and traction wheels loosely supported thereon, of duplicate fan casings, a fan in each casing, a flaring nozzle integral with each casing and having an open mouth adapted to pass over the surface to be cleaned, a brace plate bolted to each casing, a fan shaft 60 common to said fans, a driving clutch for actuating said shaft, a driving clutch for operatively connecting each wheel and the driving shaft and means for transmitting motion of the driving shaft to said fan shaft. 70

In testimony whereof we affix our signatures in presence of two witnesses.

GEORGE G. SCHUELE.
ELMER E. HGENFRITZ.
